United States Patent Office

Des. 215,070
Patented Aug. 26, 1969

215,070

• VEHICLE ACCELEROMETER

Leonard M. Snyder, 745 Linda Vista Ave.,
Pasadena, Calif. 91103

Filed Oct. 28, 1968, Ser. No. 14,210

Term of patent 14 years

Int. Cl. D10—11

U.S. Cl. D52—6

FIG. 1.

FIG. 5.

FIG. 3.

FIG. 2.

FIG. 4.

FIG. 6.

FIG. 1 is a perspective of a vehicle accelerometer illustrating my new design.

FIG. 2 is a side elevation thereof.

FIG. 3 is a front elevation thereof.

FIG. 4 is a rear elevation thereof.

FIG. 5 is a plan view thereof.

FIG. 6 is a bottom view thereof.

The essential features of the design reside in the solid line portions thereof.

I claim:

The ornamental design for a vehicle accelerometer, as shown and described.
